UNITED STATES PATENT OFFICE.

FRIEDRICH SCHREINER, OF PLAINFIELD, NEW JERSEY.

CASTING-BOX FOR STEREOTYPES.

No. 806,504.

Specification of Letters Patent.

Patented Dec. 5, 1905.

Application filed June 29, 1905. Serial No. 267,539.

To all whom it may concern:

Be it known that I, FRIEDRICH SCHREINER, a citizen of the United States, and a resident of Plainfield, in the county of Union and State of New Jersey, have invented a new and Improved Casting-Box for Stereotypes, of which the following is a full, clear, and exact description.

This invention relates to casting stereotype-plates, and constitutes an improvement upon the device patented to me October 25, 1904, the number of the said patent being 773,528. In the said patent I described a mold comprising a movable section-gage which enables plates of irregular dimensions to be cast in the same box.

The object of this invention is to provide a lifting device for the cover of such a casting-box.

20 The invention consists in the construction and combination of parts to be more fully described hereinafter and definitely set forth in the claims.

Reference is to be had to the accompanying drawings, forming a part of this specification, in which similar characters of reference indicate corresponding parts in all the figures.

Figure 1 is an elevation representing the lower portion of the frame of the machine as broken away and showing the cover of the box raised. Fig. 2 is a substantially longitudinal section through the casting-box, the cover and a portion of the bottom plate being represented in elevation. In this view the stereotype-plate is represented lying within the box after being formed therein, and the cope or cover of the box is represented in dotted outline in a raised position. 40 Fig. 3 is an end elevation of the casting-box, taken at the inlet and representing contiguous parts as broken away.

Referring more particularly to the parts, 1 represents the bottom plate of a casting-box, which is provided at its upper edge with the usual ears 2, having sockets at which a pivotal connection is made with a cover or cope 3. This cover is of the construction described in the patent to me referred to above. 50 Its lower face is composed of a plurality of tapering bosses 4, arranged in rows in such manner as to present longitudinal grooves 5 and transverse grooves 6. Near the lower edge of the bottom plate 1 a head-gage 7 is provided, which has a longitudinally-disposed plate 8 attached to the edge thereof,

which projects so as to constitute a flange, as will be readily understood. I also provide side gages 9, which are adapted to be disposed longitudinally of the bottom plate 60 near the sides thereof, as indicated. These side gages are formed on their upper edges with inwardly-projecting flanges 10, the purpose of which will appear more fully hereinafter. I provide also a matrix-gage 11, 65 which consists of a flat strip or rule adapted to be laid flat upon the plate 1, so as to constitute a gage to determine the width and thickness of the body of the stereotype. Upon this matrix-gage I lay a section-gage 70 12, which is preferably of substantially triangular form in cross-section, the side face of the same being provided with longitudinal grooves 13 for a purpose which will appear hereinafter.

7.5 Near the lower edge of the cover 3 I provide projecting brackets 14, between which there is pivotally supported an eccentrically-mounted roller or lifting-bar 15, the same being provided with a suitable handle 16, enabling it to be rotated upon its pivots 17. This roller 15 completely bridges the space between the brackets 14.

75 In using this casting-box the stereotype-matrix is laid face up upon the bottom plate 85 1 and the head-gage 7 is then laid in position near the bolster or ridge of the matrix. One or both of the side gages are then set in position. The width of the plate to be cast having been determined, the matrix-gage 11 90 would then be set into position so as to give the plate the desired width, and upon the upper side of this gage 11 the section-gage 12 is applied, as indicated in Fig. 3, the same being disposed in such a position that when the 95 cover closes down it will occupy one of the aforesaid longitudinal channels or grooves 5. The cover of the box having been closed, the parts will be clamped in position and the metal would be allowed to flow in from the 100 gate end adjacent to the lifting-bar 15. When the cover is being applied during the casting operation, the handle 16 should be folded back against the upper side of the cover, as indicated in the dotted outline in Fig. 2, so that the lifting-bar or roller 15 does not prevent the cover from seating closely into position upon the gages. After the plate has been cast the handle 16 is moved upwardly into some such position as that indicated in Fig. 2 in full lines. In this way by 105 reason of the eccentricity of the lifting-bar 110

the side gages and the section-gage are subjected to pressure and the cover is forced upwardly from the cast plates 18 and 19, (indicated, respectively, at the right and left of the section-gage 12.)

5 The flanges 10 afford means for preventing the newly-formed plate from adhering to the cover and rising therewith, and the grooves 13 have a similar function, it being understood that when the metal flows the section-gage constitutes a dam to form the side wall of the plate. In this connection it should be understood that the cross-section of the section-gage is considerably less than that of the groove or channel in which it is placed.

10 In order to diminish the wear upon the upper surface of the section-gage, this part is preferably flattened slightly, as indicated in Fig. 3.

15 Special attention is called to the fact that whatever be the width of the plate cast in the mold the lifting-bar will afford means for freeing the cover with facility, as the lifting-bar will always engage with the section-gage 25 placed at any point.

Having thus described my invention, I claim as new and desire to secure by Letters Patent—

20 1. A casting-box for stereotype-plates, comprising a bottom plate, a side gage, an in-

termediate section-gage adapted to regulate the width of plates cast, a cover adapted to overlie said bottom plate, and an eccentric lifting-bar carried by said cover and resting on said gages.

35

2. A casting-box for stereotype-plates, comprising a bottom plate, a cover coöperating therewith, side gages, an intermediate section-gage disposed therebetween and adapted to regulate the width of plates cast, 40 and an eccentric lifting-bar mounted in said cover resting upon the said side gages and said section-gage.

40

3. A casting-box for stereotype-plates, comprising a bottom plate, a cover coöperating therewith, side gages, a section-gage disposed between said side gages and constituting a dam to limit the side flow of the molten metal, said section-gage having an irregularity adapted to interlock the cast plate 45 therewith, and a transverse lifting-bar resting upon said section-gage.

45

50 In testimony whereof I have signed my name to this specification in the presence of two subscribing witnesses.

FRIEDRICH SCHREINER.
